CUSHIONING DEVICE FOR RAILROAD CARS

Otho C. Duryea, Waterbury, Conn.

Application June 8, 1937, Serial No. 147,137

16 Claims. (Cl. 267—9)

This invention relates to improvements in cushioning devices for railroad cars and it consists of the matters hereinafter described and more particularly pointed out in the appended 5 claims.

One of the objects of the present invention is to produce a cushion device of this kind including friction mechanism and at least one spring for use in railroad cars and which device, 10 upon the imposition of a load, yieldingly resists the same and absorbs the initial shock thereof and upon release of load, operates directly to return the parts to normal position.

Another object of the present invention is to 15 provide a cushioning device of this kind including a friction mechanism and a main cushioning spring that is directly engaged with the end members of the device and is operative upon release of load to return them to normal position 20 without going through the friction mechanism.

A further object of the invention is to provide 25 a cushioning device of this kind which compensates for manufacturing tolerances and consists of but a relatively few parts requiring little, if any, machine work and may be readily assembled so as to be produced at a relatively low cost.

The above-mentioned objects of the invention, 30 as well as others, together with the several advantages thereof, will more fully appear as the specification proceeds.

In the drawing:—

Fig. 1 is a longitudinal sectional view through 35 a cushioning device for railroad cars embodying the preferred form of invention, with the parts in their normal position as when not under load.

Fig. 2 is a view similar to Fig. 1 with the parts 40 in their load bearing position.

Fig. 3 is a transverse section through the device 45 of Fig. 1 as taken on the line 3—3 of Fig. 1.

Fig. 4 is a perspective view of one of the parts 50 of the cushioning device.

Fig. 5 is a perspective view of a certain friction 45 shoe or block embodied in the device and which shoe or block will be more fully referred to later.

The cushioning devices with which the present invention is more particularly concerned are those including friction mechanism and at least 50 one spring for yieldingly resisting and gradually absorbing shocks and which devices may be used for draft gear and buffer purposes as well as for snubbing the action of truck springs.

For ease of illustration, the invention is herein 55 illustrated as embodied in a device for snubbing

the action of the truck springs of a railroad car. This is to be considered only by way of illustration and not by way of limitation.

Referring now in detail to that embodiment of the invention illustrated in the drawing 10 5 and 11 indicate respectively the top and bottom load bearing members of a cushioning device in the form of a truck spring snubber adapted for insertion between a truck bolster end and the lower arch of a truck frame, not shown. As 10 shown herein both of these members are of the same pattern, shape and form. Each load bearing member, as best shown in perspective in Fig. 4, includes a radial flange-like end 12 and an 15 arcuate substantially semicylindrical body portion 13. Said load bearing members are arranged with the body portion of one member facing endwise toward the flange of the other member, the body portions of both members being arranged in longitudinal overlapping relation and 20 enclosing suitable friction mechanism as will later appear. In the end 12 of each member 10 and 11 is an axial opening 12a whereby 25 assembling of the parts of the cushioning device may be facilitated as will later appear.

Each body portion 13 is provided between its ends with an internal, tapering friction surface 14, defined at its ends by semicylindrical inner and outer end shoulders 15 and 16, respectively. Each internal tapering friction surface 14 is 30 curved transversely, the ends of said surfaces being of the same radius but struck from different centers which are off-center with respect to the center of curvature for the outer surface of the body and which outer surface is concentric 35 with the flange 12.

Between the overlapping parts of the body portions 13—13 is provided a pair of coating friction blocks or shoes 17—17, of the same shape or form and one of which appears in perspective 40 in Fig. 5. Each shoe has a longitudinal outer surface 18 that fits against the taper of an associated surface 14, a transverse end surface 19 and a diagonal friction surface 20. In each shoe is a longitudinal opening 21 and on the end surface 19 thereof, is an arcuate flange-like extension 22. This extension not only increases the area of the surface 18, but forms a shoulder for coating with the shoulder 16 of the associated member 10—11 to form a solid stop. The shoes 50 are arranged in opposed relation with the diagonal or angular friction surfaces 20—20 engaged with each other. A retainer bolt 23 of a diameter somewhat less than that of the openings 21, extends through the openings 21 in both 55

blocks or shoes, so as to permit some relative, lateral movement between said blocks or shoes.

The bolt 23, which is longer than the blocks 17, has a head 24 engaged with the transverse end face of one of the blocks 17-17. The other end of the bolt carries a flange nut 25 having spanner wrench openings 25a and a helical expansion spring 26 surrounds a part of said bolt between the flange of the nut 25 and the surface 10 19 of the adjacent friction block.

The main compression resistance and release spring 27 is of helical formation and surrounds the body portions 13 of both the members 10 and 11 and has direct engagement at its ends with 15 the flanges 12 of said members. This spring has an internal diameter providing a relatively snug fit upon the outer surfaces of said overlapping body portions 13 of both members 10 and 11 and has an external diameter approximating that of 20 the said flanges 12. Preferably the spring 27 is made from octagonal bar stock.

In the assembly of the device the nut 25 is screwed down tight to bring the various convolutions of the spring 26 into engagement to 25 make the spring solid, after which the nut is backed off for about two turns. This will open up the convolutions of the spring, to an amount which provides for the necessary relative movement between the friction blocks or shoes. Thus 30 the spring is employed to establish an initial pressure for said blocks or shoes and maintains them in initial pressure condition, the end of the bolt associated with the nut 25 being upset to prevent unscrewing of the nut.

35 In Fig. 1, the parts are shown in their normal non-load bearing position. When a load is imposed upon one or the other of the flanges 12-12 of the members 10 and 11, in the relative movement of said members toward each other, the 40 spring 27 is placed under compression and at the same time the friction grip is increased not only between the blocks 17-17 and the bodies of the members 10 and 11, but also between the blocks 17 themselves through the direct engagement of 45 their diagonal surfaces 20. The frictional engagement of the surface 13 of the members 10 and 11, respectively, with the flat inner surfaces of the convolutions of the spring 27 aids in increasing this grip. This snubs the shock of 50 compression under load. In this action, the blocks 17 move relatively axially and laterally, the enlarged openings in the blocks permitting the lateral movement and the spring 26 compressing to permit the axial movement.

55 So soon as the load which has compressed the device has been removed, the spring expands to immediately return the members to their normal position and this release occurs without the releasing action going through the friction elements. In this way the return of the members 10 and 11 to normal position is not accomplished through the friction element but only through the spring 27. When said members have thus returned to normal position, the spring 26, which 60 has been placed under compression by the relative movement of the blocks 17-17, re-expands to return the blocks to normal position wherein their relatively pointed ends engage against the stop shoulders 15. This determines the relatively 65 normal position of the members 10 and 11 when not under a load.

Fig. 2 shows the position of the parts under a load or pressure tendency to move one of the members 10-11 toward the other, but such a 70 load is shown as less than the capacity of the

cushioning device as a whole. Further relative movement of the parts toward each other would make the spring 27 go solid with the ends of the block extensions 22 engaging the shoulders 16 of the members 10 and 11. In the relative movement of the members 10 and 11 toward each other, as above described, the blocks 17-17 have less axial travel than that of the spring 27, the said blocks having a travel of about one-half of that of said spring.

10 With the cushioning device made as described, it more nearly approaches uniformity of frictional resistance throughout and the tendency to bind and remain compressed under the load imparted thereto is avoided. Therefore, upon 15 release of load, the parts instantly return to normal position and this return is afforded directly through the spring and not through the friction mechanism. By the pressure of the parts more directly associated with the friction blocks or 20 shoes 17-17, it is possible to establish and to maintain said blocks or shoes in initial pressure condition.

25 While in describing the invention, I have referred in detail to the form and arrangement of the parts of the device, the same is to be considered only in the illustrative sense so that I do not wish to be limited thereto except as may be specifically set forth in the appended claims.

30 I claim as my invention:

1. In a cushioning device for railway cars, the combination of means providing two members that are relatively movable in an axial direction toward and away from each other, means operatively secured to each member and disposed in 35 overlapping relation and cooperating to form opposed tapered internal friction surfaces, means providing shoes having frictional engagement with each other and with said opposed surfaces, a spring cooperating with said shoes in offering 40 a resistance to the movement of one of said members from its normal position toward the other of said members under the action of a load imposed upon one of said members, said spring upon release of load operating directly upon the 45 moved member to return the same to its normal position.

2. In a cushioning device for railway cars, the combination of means providing two members that are relatively movable in an axial direction 50 toward and away from each other, means operatively secured to each member and disposed in overlapping relation and cooperating to form opposed tapered internal friction surfaces, means providing shoes having frictional engagement with each other and with said opposed surfaces, a spring having direct end engagement with said members and cooperating with said shoes in offering a resistance to the movement of one of 55 said members from its normal position toward the other of said members under the action of a load imposed upon one of said members, said spring upon release of load operating directly upon the moved member to return the same to its normal position.

3. In a cushioning device for railway cars, the combination of means providing two members that are relatively movable in an axial direction toward and away from each other, means operatively secured to each member and disposed in 70 overlapping relation and cooperating to form opposed tapered internal friction surfaces, means providing shoes having frictional engagement with each other and with said opposed surfaces, a spring surrounding both of said means secured 75

to said members and providing said friction surfaces and operating at its ends against each one of said members and cooperating with said shoes in offering a resistance to the movement of one of said members from its normal position toward the other of said members under the action of a load imposed upon one of said members, said spring upon release of load operating directly upon the moved member to return the same to its normal position.

4. In a cushioning device for railway cars, the combination of means providing two members that are relatively movable in an axial direction toward or away from each other, means operatively secured to each member and disposed in overlapping relation and cooperating to form opposed tapered internal friction surfaces, means providing shoes having frictional engagement with said opposed surfaces and having frictional surfaces engaged with each other, spring pressed means associated with said shoes for holding said shoes so as to keep said frictional surfaces tightly engaged with each other and for holding said shoes in operative engagement with said tapered friction surfaces of said members, a spring operating at its ends against each one of said members and cooperating with said shoes in offering a resistance to the movement of one of said members from its normal position toward the other of said members under the action of a load imposed upon one of said members, said spring upon the release of load operating directly upon the moved member to return the same to its normal position.

5. In a cushioning device for railway cars, the combination of means providing two members that are relatively movable in an axial direction toward or away from each other, means operatively secured to each member and disposed in overlapping relation and cooperating to form opposed tapered internal friction surfaces, means providing shoes having frictional engagement with said opposed surfaces and having frictional surfaces engaged with each other, spring pressed means associated with said shoes for holding said shoes so as to keep the frictional surfaces thereof tightly engaged with each other and for holding said shoes in operative engagement with said tapered friction surfaces of said members, said means on said members and said shoes being formed to provide cooperable shoulders to limit the movement of said shoes with respect to said tapered friction surfaces, a spring operating at its ends against each one of said members and cooperating with said shoes in offering resistance to the movement of one of said members from its normal position toward the other of said members under the action of a load imposed upon one of said members, and which resistance increases as the movement increases, said spring upon release of load operating directly upon the moved member to return the same to its normal position.

6. In a cushioning device for railway cars, the combination of means providing two members that are relatively movable in an axial direction toward or away from each other, means operatively secured to each member and disposed in overlapping relation and cooperating to form opposed tapered internal friction surfaces, means providing shoes having frictional engagement with said opposed surfaces and having frictional surfaces engaged with each other, spring pressed means associated with said shoes for holding said shoes so as to keep their frictional surfaces tightly engaged with each other and for holding said

shoes in operative engagement with said tapered friction surfaces of said members, a spring operating at its ends against each one of said members and cooperating with said shoes in offering a resistance to the movement of one of said members from its normal position toward the other of said members under the action of a load imposed upon one of said members, said spring upon the release of load operating directly upon the moved member to return the same to its normal position, said spring surrounding said means on said members and the shoes associated therewith.

7. In a cushioning device for railway cars, the combination of means providing two members that are relatively movable in an axial direction toward or away from each other, means operatively secured to each member and disposed in overlapping relation and cooperating to form opposed tapered internal friction surfaces, means providing shoes having frictional engagement with said opposed surfaces and having frictional surfaces engaged with each other, spring pressed means associated with said shoes for holding said shoes so as to keep their frictional surfaces tightly engaged with each other and for holding said shoes in operative engagement with said tapered friction surfaces of said members, a second spring having its ends engaged against each of said members and cooperating with said shoes in offering a resistance to the movement of one of said members from its normal position toward the other of said members under the action of a load imposed upon one of said members, said spring upon release of load operating directly upon the moved member to return the same to its normal position.

8. In a cushioning device for railway cars, the combination of means providing two similar members that are relatively movable toward and away from each other and each member including a substantially semi-cylindrical body portion having a tapered internal friction surface, said members being arranged with said body portions in end to end overlapping relation so that said surfaces are opposed to each other, means providing a friction mechanism within said overlapped body portions and engaged with the tapered friction surfaces thereof, and a spring surrounding said body portions and arranged at its ends to exert an outward pressure against each member and cooperating with said friction mechanism in offering resistance to the relative movement of said members toward each other.

9. In a cushioning device for railway cars, the combination of means providing two similar members that are relatively movable toward and away from each other and each member including a substantially semi-cylindrical body portion having a tapered internal friction surface, said members being arranged with said body portions in end to end overlapping relation so that said surfaces are opposed to each other, means providing a friction mechanism within said overlapped body portions and engaged with the tapered friction surfaces thereof, means providing a shoulder at each end of the friction surface of each body portion, to provide stops which limit the movement of said friction mechanism relative to said body portions, and a spring surrounding said body portions and arranged at its ends to exert an outward pressure against each member and cooperating with said friction mechanism in offering resistance to the relative movement of said members toward each other.

10. In a cushioning device for railway cars, the combination of means providing two similar members that are relatively movable toward and away from each other and each member including a body portion having a tapered internal friction surface, said members being arranged with said body portions in end to end overlapping relation so that said surfaces are opposed to each other, a pair of friction shoes between said overlapping ends of said body portions, each having a surface for engagement with the internal friction surface of an associated body portion, said shoes having engaged friction surfaces arranged obliquely to the axes of said two members, means for providing and for holding said shoes under initial compression, and a spring surrounding said body portions and arranged at its ends to exert an outward pressure against each member and cooperating with said pair of friction shoes in offering resistance to the relative movement of said members toward each other.
11. In a cushioning device for railway cars, the combination of means providing two similar members that are relatively movable toward and away from each other and each member including a body portion having a tapered internal friction surface, said members being arranged with said body portions in end to end overlapping relation so that said surfaces are opposed to each other, a pair of friction shoes between said overlapping ends of said body portions, each having a surface for engagement with the internal friction surface of an associated body portion, said shoes having engaged friction surfaces arranged obliquely to the axes of said two similar members, a bolt passing through both shoes axially of said members, a spring engaged on one end of said bolt between a nut on said bolt end and one end of one of said shoes for providing and for holding said shoes under initial compression, and a spring surrounding said body portions and arranged at its ends to exert an outward pressure against each member and cooperating with said shoes in offering resistance to the relative movement of said members toward each other.
12. In a cushioning device for railway cars, the combination of means providing two similar members that are relatively movable toward and away from each other and each member including a body portion having a tapered internal friction surface, said members being arranged with said body portions in end to end overlapping relation so that said surfaces are opposed to each other, a pair of friction shoes between said overlapping ends of said body portions, each having a surface for engagement with the internal friction surface of an associated body portion, said shoes having engaged friction surfaces arranged obliquely to the axes of said two similar members, means providing a shoulder at each end of the friction surface of each body portion, each shoe normally engaging one shoulder of the friction surface of the associated body portion, means for providing and for holding said shoes under

initial compression, and a spring surrounding said body portions and arranged at its ends to exert an outward pressure against each member and cooperating with said shoes in offering a resistance to the relative movement of said members toward each other.

13. In a cushioning device for railway cars, the combination of means providing two similar members that are relatively movable toward and away from each other and each member including a body portion having a tapered internal friction surface, said members being arranged with said body portions in end to end overlapping relation so that said surfaces are opposed to each other, a pair of friction shoes disposed between said overlapping ends of said body portions, each shoe having an external friction surface engaged with the friction surface of the associated body portion but being of a length shorter than the same, said shoes being formed with engaged friction surfaces arranged obliquely to the axes of said two members, means coacting with said shoes for holding them under initial compression, and a spring surrounding said body portions and arranged at its ends to exert an outward pressure against each member and cooperating with said shoes in offering resistance to the relative movement of said members toward each other.

14. A member for use in a cushioning device of the kind described and comprising a longitudinal body portion having an outwardly extending radial flange at one end defining a central opening for said end of said member, said body portion having a longitudinally tapered internal friction surface, and means providing shoulders at the ends of said internal friction surface.

15. A member for use in a cushioning device of the kind described and comprising a longitudinal body portion having an outwardly extending radial flange at one end defining a central opening for said end of said member, said body portion having a longitudinally tapered internal friction surface and a substantially semi-cylindrical external surface substantially concentric with the axis of said flange.

16. A friction mechanism assembly for a cushioning device of the kind described comprising a pair of similar members, each having a longitudinal outer, semi-cylindrical surface, a transverse end surface and an oblique surface between one side of said end surface and the other end of the said semi-cylindrical surface, each member having a longitudinal central opening, said members being arranged with their oblique friction surfaces engaged with each other so that the said transverse end surfaces are disposed at opposite ends of the assembly, a bolt extending through the longitudinal openings in both members, a nut carried on one end of the bolt and a spring surrounding said end of the bolt and engaged at its ends with said nut and the transverse end of one of said members.
